(57) **CLAIM**

We claim the ornamental design for a mobile computing device, as shown and described.

DESCRIPTION

FIG. 1 is a first perspective view of a mobile computing device;

FIG. 2 is a second perspective view thereof;

FIG. 3 is a front view thereof;

FIG. 4 is a back view thereof;

FIG. 5 is a first side view thereof;

FIG. 6 is a second side view thereof;

FIG. 7 is a top view thereof; and,

FIG. 8 is a bottom view thereof.

The broken lines and unshaded portions contained within broken lines depict unclaimed features of the mobile computing device that form no part of the design claim but are shown for illustrative purposes.
